(57) **CLAIM**

The ornamental design for a crib rail cover, as shown and described.

DESCRIPTION

FIG. 1 illustrates a bottom perspective view of a crib rail cover showing my new design;

FIG. 2 illustrates a top perspective view thereof;

FIG. 3 illustrates a front view thereof;

FIG. 4 illustrates a left side view thereof, the right side view being a mirror image thereof;

FIG. 5 illustrates a top plan view thereof; and,

FIG. 6 illustrates a bottom plan view thereof.

The portions of the crib rail cover between the break lines forms no part of the claimed design

1 Claim, 5 Drawing Sheets
